EARRING ATTACHMENT

John Carroll, Jr., Providence, R. I.

Application June 14, 1950, Serial No. 10,509

Term of patent 14 years

(Cl. D45—9)

To all whom it may concern:

Be it known that I, John Carroll, Jr., a citizen of the United States, residing at Providence, in the county of Providence and State of Rhode Island, have invented a new, original, and ornamental Design for an Earring Attachment, of which the following is a specification, reference being had to the accompanying drawing, forming part thereof.

Fig. 1 is a side elevation of an earring attachment, showing my new design.

Fig. 2 is a front view of the same.

I claim:

The ornamental design for an earring attachment, as shown.

JOHN CARROLL, JR.
